UNITED STATES PATENT OFFICE.

ROBERT R. POLLAK, OF SAN FRANCISCO, CALIFORNIA.

OIL-WELL RIG.

1,244,240.

Specification of Letters Patent. Patented Oct. 23, 1917.

Application filed May 18, 1914. Serial No. 839,268.

To all whom it may concern:

Be it known that I, ROBERT R. POLLAK, a citizen of the United States, residing at San Francisco, in the county of San Francisco and State of California, have invented new and useful Improvements in Oil-Well Rigs, of which the following is a specification.

The present invention relates to improvements in oil well rigs, the object of the invention being to provide means whereby the walking beams of such rigs can be supported upon the samson posts at various heights so as to allow a plurality of standard or shorter joints of the casing to be lowered into position at the same operation, thereby facilitating drilling in cavity or other formations, and subsequently allowing of the pumping of the well with the same equipment, thus saving time and expense. A further object of the invention is to provide means whereby the travel, blow or kick of the outboard or derrick end of the beam can be varied without altering its lateral or longitudinal location or the positions of the supporting or hoisting posts. A further object of the invention is to provide improved long link arms for casing hangers adapted for use with the above improved means for supporting walking beams.

In the accompanying drawings, Figure 1 is a broken side elevation of my improved deep well rig; Fig. 2 is an enlarged side view of means for pivotally supporting a walking beam; Fig. 3 is a broken side elevation 35 taken at right angles to that of Fig. 1; Fig. 4 is a broken side view of a casing hanger; Fig. 5 is a broken edge view of the same partly in section; Fig. 6 is a side view of a modified form of walking beam; Fig. 7 is 40 an enlarged cross-sectional view of the same.

Referring to the drawing, 1 indicates a derrick frame, and 2 a truss-work samson post at the side of said frame, having an upper section 3, and secured to the lower section by a spliced frame 4, removable, so that the upper section of the samson post can be detached from the lower section. The lower section of said post is braced by bars 6, and the upper section 3 is also braced by bars 7. Said bars 7 and other elements connected to, or supported on, said upper section can be removed at one time with the upper section when required for use in a drilling operation in another location, leaving the lower section of the samson post, the

lower beam and accessories intact for pumping and other necessary work, and can be re-installed when further or deeper drilling operations are required. This construction decreases the expense of installation. Secured 60 at the sides of said post 2, are upper and lower pairs of reinforcing plates 9 having holes 12 through which the trunnions 14 extend, and upon which are secured angle-plates 10 supporting journal boxes 13. In 65 said boxes 13 are trunnions 14, extending from trunnion bearings 15 adjustably secured by means of series of holes 19 to reinforcing plates 16 secured to the sides of upper and lower walking beams 17 either in 70 the form of I-beams, as shown in Figs. 1 and 2, or of the box girder type, as shown in Figs. 6 and 7, which walking beams and reinforcing plates are longitudinally slotted, as shown at 18, the walking beams extending 75 through the samson post, which is provided above and below the same with transverse strengthening plates 8.

To the outer ends of said walking beams are secured respectively long and short pitmen 21, 22, the lower ends of which are secured to the end of a crank arm 23 on the shaft 24 of a wheel 25 driven by an engine in the usual manner. 20 indicates floorings or decks below the beam bearings for the 85 purpose of conveniently adjusting said bearings.

The object of providing adjustable bearings is to vary the kick, travel and throw of the outer end of the beam according to 90 the desire of the driller. Moreover the fact that the working arm of the walking beam is longer than the power arm causes the oscillation of the derrick end of the beam to be more nearly rectilinear.

26 indicates a support for a headache post, supported upon the side of the derrick, which supports the upper walking beam when it is detached from the pitman, and which can be swung out of the way when not in use, 100 thus allowing more available walking space and less interference inside the derrick frame below the upper beam. 27 indicates a lower headache post, for supporting the lower walking beam, braced to corners of the derrick at the top of the post by braces 28.

29 indicates a platform having counterweights 31, and resting upon an I-beam 32 secured to vertical beams 33, the upper and lower ends of which are secured to horizon- 110

tal beams 34 extending inwardly from the side of the derrick. The platform is hinged, as shown at 35, and, being counter-weighted, can be quickly swung out of the way by 5 means of block and tackle, hoists, or other devices of like character. It is secured in either the upright or the horizontal position by locking stays 36. Its outer end is supported when in use by chains 37, of 10 which the lower ends are secured to the outer end of the platform and the upper ends are secured to the derrick, said chains hanging in loops when the platform is not in use. When hoisted from its horizontal 15 position free access is obtained to the space in its proximity, and when reestablished in its usual horizontal position, it is below the upper beam 17 at such a level that the driller can use it as a suitable station for 20 operating the temper screw, brakes, control and the like. The platform may be either one swung from one side, as shown, or may consist of two swung from opposite sides to meet each other and make a complete 25 floor at the section of the derrick to which it is attached. The central portion of the platform is recessed from the outer edge for the admission and clearance of the drilling, pumping and other necessary 30 appliances, and also to clear the upper beam 17 when the platform is in the upright position. This platform is provided with a safety rail 30 and also with a flexible rail 25 around the edge for the greater safety 35 of the driller. The flexible rail at the outer or free edge of the platform is detachable so that the platform when raised can pass by the beam without interference.

On the ends of the beams are detachable 40 end pieces 37^a, rigidly secured in position according to the requirements of space in the operations about the well. Each end piece comprises upper and lower plates 71, 72 connected at the sides to upright plates 45 73 and converging toward their outer ends. The plates 71, 72 fit over and under the upper and lower sides respectively of the ends of the walking beam. All the end pieces 37^a are so detachable, and they are 50 made of similar form and interchangeable, so that any end piece may be used on either end of any beam. The beams are also interchangeable, and, in case it is desired to use any one beam in any beam bearing, it 55 can be hoisted from one level to another. The upper beam can be removed, if necessary, by taking off the top of the samson post, and can be used in another derrick of similar design. Thus, in using a number 60 of derricks of this construction, it is necessary to install as a general rule only one beam for each derrick, reserving an extra beam for use in any one of the derricks by installing the same when desired, or for 65 other operations than that of pumping.

The advantage of employing a multiple system of walking beams at different levels is that the derrick end of the beam may be at such a height as to permit the insertion of at least two additional standard joints, 70 or more shorter joints, of the casing above the cellar floor, thereby facilitating drilling through cavity or other formations, and also to permit the same equipment to be subsequently used for pumping in oil wells, thus 75 saving time and expense.

38 indicates a swinging jib crane placed upon an upright post 39 braced by a horizontal brace 40 from the derrick and furnished with a traveling trolley, and a series 80 of eye-bolts 41 or anchors, fastened at intervals along the vertical post 39 for attaching hoisting tackle 42 secured to anchors 43 on the walking beams. As an optional design there may be employed a swinging 85 crane, similar to that shown at 38 but connected with the frame work on the side of the derrick opposite to the swinging jib crane 38.

The rods to the brakes of the calf-wheel 90 50, bull wheel 51, sand reel control 52, sprocket clutch 53, reverse control 54, links and steam control 56 have extensions 59 to points waist high above the upper platform level, so that the driller can have entire control of all equipment and machinery while working on said upper platform.

Rollers 58 across the opening at the hinged end or ends of the platform or platforms prevent abrasion of the casing lines, hoist- 100 ing lines and the like.

60 indicates a hanger arm the middle portion of which is formed of pairs of angle irons 61, between which are interposed brace rods 62 riveted or bolted to each other and 105 to the angle irons in lattice form. Between the end portions of the angle irons are inserted plates 63 and on opposite sides of said plates 63 at both ends, and abutting against the angle irons, are plates 64, to 110 which, and to the angle irons, are riveted, as shown at 65, plates 66. The plates 63 and 64 are riveted together by countersunk rivets 67. The plates 63 and 64 have formed therethrough at the upper end a circular hole 68 and at the lower end a longitudinal slot 69.

In operation two of these improved long link arms are ordinarily used to support the casing. The lower slotted ends of the 120 arms support a spider, trunnion or other clamping device passing to the top of the casing, and the upper ends of said arms are suspended from a pin or bearing, which in turn is hung from the calf-wheel line. This 125 construction permits the casing to be raised or lowered at will, but does not permit of any buckling or bending of the casing, or of the hanger, due to the downward motion of the casing being temporarily retarded 130.

when sinking the casing into the well, inasmuch as slack, which would ordinarily appear by paying off the calf-wheel line, would be taken up by the length of the slots 5 at the lower ends of said long link arms.

The design of these arms is such that they can be easily handled, owing to their compactness and lightness, and yet can be easily manufactured. At the same time they are 10 economical, rigid and strong, and the parts can be easily renewed. Moreover, this construction permits of the hanger being easily made in sections which can be bolted or riveted together in the derrick chamber, and 15 thus permits hangers to be used of much greater length than with the old style, in which they are made of a single forged piece. Longer casing hangers permit the casing to be more readily drawn out to clean 20 the well and expedite the drilling operation, and allows the completion of the well in a shorter time, thereby reducing the expense of drilling.

A further advantage of this construction 25 resides in the ease of renewal of any broken parts, which can be replaced in the field, the repaired arms being as strong, symmetrical, and homogeneous as originally fabricated. This advantage is increased by 30 the fact that it is extremely difficult to repair forged hangers, if breakage occurs, since facilities for scarfing and welding the forgings are not available in the oil fields. Furthermore, the time for such welding is 35 necessarily considerable, thereby causing delay in the drilling operations, with a corresponding accumulation of expense. In fact, the broken parts of the forged hanger would ordinarily be thrown away with re- 40 sulting loss, whereas the structural steel arms can be quickly renewed if necessary.

A further advantage resides in the fact 45 that my improved hanger weighs about one-third or one-half of the weight of the old style forged hanger, at the same time having the same tensile strength with increased transverse stiffness. This allows the hanger and casing to be manipulated more easily than the old style of heavy forged hangers.

50 I claim:—

1. In combination with a derrick frame, a samson post at the side of said frame, upper and lower walking beams removably pivoted on said post, and a platform be- 5 between the two walking beams and movably supported by said derrick.

2. In combination with a derrick frame, a samson post at the side of said frame, upper and lower walking beams removably pivoted on said post, and a platform be- 60 tween the two walking beams and movably supported by said derrick, an edge of the

platform being recessed at its central portion.

3. In combination with a derrick frame, 65 a samson post at the side of said frame, interchangeable upper and lower walking beams pivoted on said post, and a platform between the two walking beams and movably supported by said derrick, the free edge of 70 the platform being recessed at its central portion.

4. In combination with a derrick frame, a samson post at the side of said frame, interchangeable upper and lower walking 75 beams pivoted on and extending through the samson post, and a platform between the two walking beams and movably supported by said derrick, a free edge of the platform being recessed at its central portion. 80

5. In combination with a derrick frame, a samson post at the side of said frame, interchangeable upper and lower walking beams supported on the samson post, a support supported upon the side of the der- 85 rick and extending inwardly therefrom, a counter-weighted platform between the walking beams and hinged upon said support, and means for supporting the outer edge of the platform, said outer edge being 90 recessed at its central portion.

6. In combination with a derrick frame, a samson post at the side of said frame, interchangeable upper and lower walking beams pivotally supported on said post, and 95 detachable end pieces on the ends of the beams.

7. In combination, a samson post, pairs of reinforcing plates secured to the sides of said post, angle plates secured to said re- 100inforcing plates, journal boxes supported by said angle plates, a walking beam, trunnion bearings rigid with said walking beam, said walking beam being longitudinally slotted and extending through the samson post, 105 trunnions in said bearings and boxes, and strengthening plates secured to said samson post above and below the walking beam.

8. In combination, a samson post, having a lower section, an upper section, a slide 110 frame securing the upper section to the lower section, and bars bracing the upper section, said upper section and bars being removable simultaneously, and upper and lower walking beams pivoted on the said 115 sections respectively.

In testimony whereof I have hereunto set my hand in the presence of two subscribing witnesses.

ROBERT R. POLLAK.
